UNITED STATES PATENT OFFICE.

FRANK B. MOREHOUSE AND WILLIAM H. KLEINHAMMER, OF SAN FRANCISCO, CALIFORNIA, ASSIGNEES, BY DIRECT AND MESNE ASSIGNMENTS, TO TRAYWAY MFG. CO., A CORPORATION OF CALIFORNIA.

WRINGER.

Application filed October 30, 1923. Serial No. 671,731.

The invention relates to wringers for expressing water from clothes and other fabrics and relates particularly to a power driven wringer although certain features of 5 the wringer may be embodied, with equal success, in hand operated wringers.

An object of the invention is to provide a wringer in which the line of contact between the wringer rolls is clearly and definitely 10 disclosed.

Another object of the invention is to provide means for immediately relieving the pressure of the rolls upon each other when desired.

15 Another object of the invention is to provide a wringer in which the pressure on the rolls may be relieved or established with a minimum of effort.

Another object of the invention is to provide 20 a wringer in which the upper roll is entirely released from the wringer when the pressure of the rolls is released.

The invention possesses other advantageous features, some of which, with the 25 foregoing, will be set forth at length in the following description, where we shall outline in full, the form of the invention which we have selected for illustration in the drawings accompanying and forming 30 part of the present specification. In said drawings we have shown one form of wringer embodying our invention, but it is to be understood that we do not limit ourselves to such form, since the invention, as set forth 35 in the claims, may be embodied in a plurality of forms.

Referring to said drawings:—

Figure 1 is a front elevation of a wringer embodying our invention.

40 Figure 2 is a side elevation of the wringer with the parts in position to place the rolls under pressure.

Figure 3 is a side elevation of the wringer with the parts in position to release the 45 upper roll.

Figure 4 is a perspective view of one of the mountings of the upper wringer roll.

The wringer of our invention comprises a stationary support consisting of the end 50 plates 3 in which the lower roll 4 is journalled. The roll 4 is provided with a driving shaft 5 which may be operated by hand or power. Each side plate 3 is provided on its outer surface with an ear 6 to which a

curved flat spring 7 is secured. The upper 55 roll 8 is journalled in the free end of the spring 7 and the spring is so constructed that it exerts a downward pressure on the upper roll 8, pressing it against the lower roll 4, so that water is expressed from fabric 60 passing between the rolls. The spring 7 is resilient and permits the upper roll 8 to move upward when material is disposed between the rolls.

The rolls 4 and 8 are made of contrasting 65 appearance, preferably by making the two rolls of different color, so that the line of contact of the rolls is always definitely disclosed, thus obviating the necessity of the housewife feeling for the line of contact and 70 sometimes having her fingers caught, due to the obscurity of the line of contact. We prefer to make the rolls of different colors, for instance the lower roll white and the upper roll blue, but the same desirable effect 75 may be obtained by forming designs of different configuration on the surfaces of the rollers, so that the interruption of the designs on the two rollers will clearly indicate 80 the line of contact.

Means are provided for releasing the pressure of the rolls and for releasing the upper roll from its bearing. Each spring 7 is provided on its end with a cylindrical bearing member 12 which is preferably integral with 85 the spring. The bearing member 12 is preferably disposed vertically above the axis of the roll 4 and is pressed downward towards the roll 4 by the spring 7. Journalled in the bearings 12 are the trunnions 13 of 90 the release member 14 which normally overlies the upper roll 8. The trunnions 13 of the release member 14 are provided with eccentrically disposed bearings 15 which open laterally onto the faces of the trunnions. 95 Disposed in the bearings 15 are the trunnions or shaft ends 16 of the upper roller 8. By virtue of the fact that the bearings 15 open laterally onto the surface of the trunnions 13, the shaft ends 16 of the roller may be readily dropped into these bearings. To permit the removal of the roller 8 from the bearings 15 the cylindrical bearing members 12 are each provided with an aperture or notch 17 cut into the bearing member 12 from the inner edge thereof. The shaft ends 16 are of 100 such length that they will pass laterally through the apertures 17 into the bearings 15.

when the aperture in the bearing is alined with the aperture 17. The trunnions 13 are rotatable in the bearings 12 to expose the bearing 15 in the aperture 17 so that the roll 8 may be readily removed and replaced. The trunnions 13 are rotated by moving the release member 14 and the movement of this member is limited by the pin 18 which extends into the aperture 17. When the member 14 is in its backward position the pin 18 lies in the notch 19 so that it will not interfere with the outward movement of the shaft end 16, from the bearing.

Normally the parts are in the position shown in Figure 2, the spring serving to press the rolls together. In this position, the axis of the trunnion 13 is slightly displaced from the line of dead center of the axes of the two rolls 4 and 8 so that the pressure of the rolls does not tend to rotate the release member 14 and thus relieve the pressure on the roll. The axis of the trunnion 13 is slightly in front of the line through the axis of the rolls so that the parts are securely held in operative position. When it becomes necessary or desirable to relieve the pressure of the rolls, the release member is moved backward by a slight pressure of the hand and when the center of the trunnion passes dead center, the release member springs into the position shown in Figure 3. With the release member in this position, the trunnion 13 has rotated sufficiently to bring the opening of the bearing 15 into registry with the aperture 17 so that the roll 8 is freed and may be lifted from the wringer.

Means are provided for receiving the pressure of the springs 7 when the release member is operated so that the pressure may be transferred from the wringer rolls. Disposed on the plate 3 below the bearing member 12 is a stop 21 with which the bearing member contacts as the trunnion 13 is rotated. The pressure of the spring is thus transferred from the roller 8 to the stop 21 so that the roller 8 is entirely free and may be removed from the wringer. With the shaft ends 16 of the roller 8 in position in the bearings 15, and with any obstruction removed from between the rolls, the release member may be easily moved forward to the position shown in Figure 2, such movement serving to lock the shaft ends 16 in their bearings and to transfer the pressure of the springs from the stop 21 to the roller 8.

We claim:

1. In a wringer, a pair of movable bearings each having a lateral aperture therein, a release member, trunnions on said release

member journalled in said bearings, each of said trunnions having a bearing therein opening laterally on the face of the trunnion and adapted to register with said aperture, a roll, and trunnions on the roll seated 65 in the bearings in the trunnions of the release member.

2. In a wringer, a pair of movable bearings each having a lateral aperture therein, a release member, trunnions on said release 70 member journalled in said bearings, each of said trunnions having an eccentric bearing therein opening laterally on the face of the trunnion and adapted in one position to register with said aperture, a roll, and trunnions on said roll adapted to be moved 75 through said apertures into and out of said eccentric bearings.

3. In a wringer, a stationary frame, a movable normally upright release member having bearings, an upper wringer roll journalled in said bearings, means for operatively connecting said release member to said stationary frame, means for freeing the upper roll from said release member upon movement of said member to an inclined position, and means for causing said roll to be retained in operative position upon movement of said member to its upright position.

4. In a wringer, a pair of rolls normally 90 mounted in superposed relation, spring means for resiliently pressing said rolls together, means for varying the pressure between said rolls including a manually controlled lever having limited movement to 95 either one of two positions, means associated with said lever whereby manual movement of said lever to one position supplies the energy to cause said spring means to increase the pressure between said bearings, and 100 movement to the other position causing the pressure between said rolls to be relieved, and means for releasing one of said rolls from its mounting when said lever is in said second position only.

5. A wringer comprising a stationary support in which is journalled a lower wringer roll, spring arms provided with apertured bearings carried by said stationary support, a rotatable release member journalled in said bearings and normally closing said apertures, and an upper wringer roll eccentrically supported within said bearings and releasably secured therein by said release member when said apertures are closed.

In testimony whereof, we have hereunto set our hands.

FRANK B. MOREHOUSE.
WILLIAM H. KLEINHAMMER.
